UNITED STATES PATENT OFFICE

2,568,182

WIRE TENSION CONTROL UNIT

James A. Anania, Newark, N. J., assignor of one
half to Carmine Paul Policastro, North Arling-
ton, N. J.

Application August 6, 1948, Serial No. 42,962

5 Claims. (Cl. 242—156)

1

This invention relates to a wire tension control device.

It is an object of the present invention to provide a wire tension control device adapted to receive a spool of wire and to have that spool resisted by a brake element on the yoke retaining spool and wherein there is an upwardly extending and vertically adjustable and spring supported pulley located ahead of the spool and having sufficient flexibility to adapt itself to the different sides of the spool and the wire being relieved therefrom.

Other objects of the present invention are to provide a wire tension device which is of simple construction, easy to adjust, inexpensive to manufacture, convenient to use, sturdy and compact, and efficient in operation.

For other objects and for a better understanding of the invention, reference may be had to the following detailed description taken in connection with the accompanying drawing, in which

Fig. 1 is a side elevational view of the wire tension device embodying the features of the present invention.

Fig. 2 is a top plan view of the device.

Fig. 3 is a sectional view in elevation, taken on line 3—3 of Fig. 1.

Fig. 4 is a fragmentary sectional view taken on line 4—4 of Fig. 1.

Fig. 5 is a fragmentary sectional view, in elevation, taken on line 5—5 of Fig. 4.

Fig. 6 is a fragmentary transverse sectional view taken on line 6—6 of Fig. 3.

Fig. 7 is a sectional view, in elevation, taken on line 7—7 of Fig. 3 and looking upon the engaging face of the brake element.

Referring now to the figures, 10 represents a base adapted to be attached by screws 11 to a top surface. This base has an upwardly extending portion 12 with openings therein for receiving the lower ends of laterally spaced vertical support members 13 and 14. These members are secured together by a thumb screw 15 to retain a central support 16 having an elongated slot 17 therein. Between the vertical supports 13 and 14 and extending through the elongated slot is a pin 18 serving to limit the upward adjustment of the support 16 and to prevent the same from pulling out of the upper ends of the supports 13 and 14.

Secured to the upper end of the support 16 by screws 19, is a U-shaped member or yoke 20 for supporting a wire spool 21. The sides of the yoke have slots 22 to receive shaft extensions

2

23 of the spool 21. The shaft extensions 23 extend through ball bearing elements 24 adapted to be retained respectively within the notches or slots 22.

Pivotedly connected to the lower part of the yoke is a brake element 26 extending upwardly and adapted to engage the side of the spool whereby to resist the rotation of the same. The element 26 is held in frictional engagement with the spool by a spring 27 lying within an opening in the side of the yoke and retained therein by an adjustable thumb screw 28. By adjusting this screw, the tension of the spring can be adjusted and accordingly the brake element 26 will be made to have more frictional engagement with the spool 21.

Connected to the vertical support 14 by a thumb screw 29 is a laterally extending supporting arm 31 for a pulley guide device 32. The supporting arm 31 has a longitudinally extending slot 33 so that the arm can be extended to different distances from the vertical support and the guide device 32 adjusted toward or away from the spool 21.

The pulley guide device 32 comprises a pulley 34 which is journaled in a yoke 35 fixed to the upper end of a free coil spring 36. The lower end of the coil spring is connected to a threaded rod 37 having an adjusting nut 38 which may be turned to place the pulley 34 at different elevations. The nut 38 rests on the top of a coupling element 39 which is secured to the arm 31 by a thumb screw 41. This same thumb screw 41 will secure the rod 37, or that portion of the same which extends into the coupling member 39, to the coupling member 39.

In operation, the spool 21 having wire thereon is placed in the upper end of the yoke 20 and its wire is extended over the pulley 34 as shown in Fig. 1 and is pulled off the spool. Because of the pulley 34 being mounted on a free spring, the pulley can adjust itself laterally as the wire is taken off the spool from one side to the other. As more of the wire is taken from the spool so that it extends from a different elevation, the adjusting nut 38 of the pulley device can be adjusted to lower the pulley 34.

While various changes may be made in the detail construction, it shall be understood that such changes shall be within the spirit and scope of the present invention as defined by the appended claims.

I claim:

1. A wire tension control device comprising a base, vertical support means extending up-

wardly from the base, a yoke secured to the upper end of the vertical support means, a spool of wire removably secured to the yoke, a laterally extending arm adjustably connected to the vertical support means and extending to one side thereof, and a wire guide device supported on the laterally extending arm and comprising a pulley, an attaching member, and a free spring secured between the pulley and the attaching member, said pulley adapted to receive the wire extending from the spool and follow the wire from side to side as it is released from the spool.

2. A wire tension control device comprising a base, vertical support means extending upwardly from the base, a yoke secured to the upper end of the vertical support means, a spool of wire removably secured to the yoke, a laterally extending arm adjustably connected to the vertical support means and extending to one side thereof, and a wire guide device supported on the laterally extending arm and comprising a pulley, an attaching member, and a free spring secured between the pulley and the attaching member, said pulley adapted to receive the wire extending from the spool and follow the wire from side to side as it is released from the spool, and a brake element on the yoke adapted to engage with the side of the spool for regulating the resistance to the movement of the spool and the tension of the wire.

3. A wire tension control device comprising a base, vertical support means extending upwardly from the base, a yoke secured to the upper end of the vertical support means, a spool of wire removably secured to the yoke, a laterally extending arm adjustably connected to the vertical support means and extending to one side thereof, and a wire guide device supported on the laterally extending arm and comprising a pulley, an attaching member, and a free spring secured between the pulley and the attaching member, said pulley adapted to receive the wire extending from the spool and follow the wire from side to side as it is released from the spool, and the attaching member of the pulley guide device

5 having an adjustable member thereon for supporting the guide device on the arm at different elevations, a coupling member receiving the attaching member and a thumb screw for securing the coupling member to the arm and for securing the attaching member to the coupling member.

10 4. A wire tension control device comprising a base, vertical support means extending upwardly from the base, a yoke secured to the upper end of the vertical support means, a spool of wire removably secured to the yoke, a laterally extending arm connected to the vertical support means and extending to one side thereof, and a wire guide device supported on the laterally 15 extending arm and comprising a pulley, an attaching member, and a free spring secured between the pulley and the attaching member, said pulley adapted to receive the wire extending from the spool and follow the wire from side to side as it is released from the spool, and said laterally extending arm having a longitudinally extending slot, a thumb screw extending through the slot adapted to be secured to the vertical supporting means whereby to retain the laterally 20 extending arm at its adjusted position and to locate the pulley device at different distances from the wire spool.

25 5. A wire tension control device as defined in claim 1, and means connecting the yoke to the vertical supports for vertical adjustment relative thereto.

JAMES A. ANANIA.
